Frank J. Benes, Lancaster, Ohio, assignor to Anchor
Hocking Glass Corporation, Lancaster, Ohio, a cor-
poration of Delaware

Filed May 31, 1967, Ser. No. 7,309

Term of patent 14 years

(Cl. D36—2)

FIG. 1 is an elevational view of a covered candy dish or similar article showing my new design;

FIG. 2 is a bottom plan view;

FIG. 3 is a sectional view on line 3—3 of FIG. 1;

FIG. 4 is a detailed development view of the design of a portion of the pattern on the side of the candy dish;

FIG. 5 is a detail view of a portion of the pattern on the cover member;

FIG. 6 is a sectional view on line 6—6 of FIG. 1;

FIG. 7 is a sectional view on line 7—7 of FIG. 1;

FIG. 8 is a sectional view on line 8—8 of FIG. 3; and

FIG. 9 is an exploded elevational view.

It is understood that the patterns shown fragmentarily in full lines are continued about the entire article in the paths indicated by the broken lines.

I claim:

The ornamental design for a covered candy dish or similar article, substantially as shown and described.
